ROTO DART GAME

Leon E. Moss and Paul M. Titus, Paulsboro, N. J., assignors of one-fourth to W. Clayton Apgar, Woodbury, N. J., and one-fourth to Max Glickman, Paulsboro, N. J.

Application June 10, 1936, Serial No. 84,544

6 Claims. (Cl. 273—102)

This invention relates to a dart game apparatus and it aims to provide a novel construction of such a game of skill for amusement, which has a revolving center serving as the target for the darts designed to add to the fascination, sport, and skill involved.

The more specific objects and advantages will become apparent from a consideration of the description following taken in connection with accompanying drawing, illustrating an operative embodiment.

In said drawing:—

Figure 1 is a view of the apparatus in front elevation;

Figure 2 is a view of the apparatus in rear elevation;

Figure 3 is a vertical sectional view taken on the line 3—3 of Figure 2;

Figure 4 is a fragmentary sectional view taken on the line 4—4 of Figure 2;

Figure 5 is a view corresponding to Figure 4 but taken through a modified form; and

Figure 6 is a detail section taken on the line 6—6 of Figure 5.

Referring specifically to the drawing wherein like reference characters designate like or similar parts, the apparatus comprises a stationary board or panel at 10 having a central round opening 11 therethrough. Suitably attached to the rear of the board as at 12, is a spider or bracket 13 having a central bearing 14.

A spindle is provided in the form of a bolt 15, having a screw-threaded portion 16 adjustably threaded in the bearing 14 and held in adjusted position by lock nuts 17 engaging the threads 16 and the opposite end of the bearing 14.

Journalized on a smooth cylindrical portion 18 of the spindle 15 is a plate 19 which is held in place by the head 20 of the bolt and by a plate 21 and a series of lock nuts 22.

Located within the opening 11 is a disc target or plate 23 which is removably screwed at 24 to the plate 19 so that the same may be removed when desired and other target discs substituted therefor. The target disc on its face is divided into segments or sections colored in any desired manner, usually red and blue, with additional sections bearing numbers. Darts are adapted to be thrown against the target disc 23 and the score will be determined by the segments or spaces which the dart strikes.

According to the present invention, the target disc is adapted to rotate at the time the darts are thrown to render the playing of the game more fascinating. To this end, a casing 25 is

fastened by brackets 26 to the board 10 and it contains an electric motor 27 whose main shaft is designated 28 and has a governor mechanism 29 slidable along the same and rotatable with it and carrying a friction disc at 30. Said friction disc 30 is adapted to engage a friction disc 31 on a shaft 32 journaled in a bearing 33 in one side of the casing 25. Keyed to the shaft 32 is a small friction wheel 34 which frictionally engages the periphery of the disc or plate 19.

Accordingly when the motor operates, the shaft 32 will be driven and will accordingly drive the pulley 34, plate 19, and the target disc 23.

Various changes may be resorted to within the spirit and scope of the invention, and for instance the form shown in Figures 5 and 6 may be utilized. This form differs from the preceding form only with respect to the drive from a shaft 28', similar to that at 28, to a shaft 32' similar to that at 32. In the present case, the shaft 28' has a worm 35 keyed thereto which is enmeshed with a worm wheel 36 keyed to the shaft 32'. The construction otherwise and the operation is the same.

We claim as our invention:—

1. A dart game apparatus of the class described comprising a board having an opening therethrough, a bracket thereon crossing the opening, means in said opening at which a dart is adapted to be thrown, means on the bracket journaling the first-mentioned means, and means on the board operable to rotate the first-mentioned means.

2. A dart game apparatus of the class described comprising a board having an opening therethrough, a spider thereon crossing the opening, a disc target in said opening, a spindle on the spider on which the target is journaled, a prime mover on the board, and gearing operated by the prime mover to rotate the disc target.

3. A dart game apparatus of the class described comprising a board, a spider thereon, a spindle mounted by the spider, a plate journaled on the spindle, a disc target carried by the plate, a prime mover mounted on the board, and gearing between the prime mover and the periphery of the plate to rotate the plate and target.

4. A dart game apparatus of the class described comprising a board, a spider thereon, a spindle mounted by the spider, a plate journaled on the spindle, a disc target carried by the plate, a prime mover mounted on the board, gearing between the prime mover and the periphery of the plate to rotate the plate and target, said spider having a bearing, said spindle having screw-

- threads engaging screw-threads of the bearing, a head on the spindle, abutment means engaging screw-threads of the spindle, said plates being located between the head and abutment means.
5. A dart game apparatus of the class described comprising a board, a spider thereon, a spindle mounted by the spider, a plate journaled on the spindle, a disc target carried by the plate, a prime mover mounted on the board, and gearing between the prime mover and the periphery of the plate to rotate the plate and target, a casing on the board carrying the prime mover, a shaft extending laterally from the casing driven by the prime mover, and a gear on the shaft driving said plate.

6. A dart game apparatus of the class described comprising a board, a spider thereon, a spindle mounted by the spider, a plate journaled on the spindle, a disc target carried by the plate, a prime mover mounted on the board, and gearing between the prime mover and the periphery of the plate to rotate the plate and target, a casing on the board carrying the prime mover, a shaft extending laterally from the casing driven by the prime mover, a gear on the shaft driving said plate, and a governor controlled drive from the shaft to the motor.
